UNITED STATES PATENT OFFICE.

MOVSESS B. ADOM, OF WHITE PLAINS, NEW YORK.

SHELL.

1,282,517.

Specification of Letters Patent.

Patented Oct. 22, 1918.

Application filed December 17, 1917. Serial No. 207,610.

To all whom it may concern:

Be it known that I, MOVSESS B. ADOM, a citizen of the United States, and a resident of White Plains, in the county of West-
5 chester and State of New York, have invented a new and Improved Shell, of which the following is a full, clear, and exact description.

My invention relates to a shell of the in-
10 cendiary type, and has reference more particularly to the mixture in the shell.

Another object of the invention is to pro-
vide a shell having a mixture which does not
need a detonating compound or fuse, and by
15 means of which any of the propeller expl-
osives may be sent off by a shock.

A further object of the invention is to pro-
vide an explosive which is inexpensive and
can be easily prepared just before it is to be
20 used.

With the above and other objects in view,
the nature of which will more fully appear
as the description proceeds, the invention
25 consists in the novel construction, combina-
tion and arrangement of parts as herein fully
described, illustrated and claimed.

I attain the above and other objects of my
invention by the structure conventionally
disclosed in the accompanying drawing.

30 Referring to the drawing, 1 is the shell
body. It has an opening through which the
same may be filled with suitable propelling
explosive 2. This explosive may be of the
gun cotton type. It is so packed into the
35 shell as to form a well alining with the open-
ing in the shell to receive a core 3 formed of
a mixture of potassium chlorate moistened
with the terpene or benzene series of the hy-
drocarbon derivatives. Preferably oil of
40 turpentine is used for the purpose. The mix-
ture of the chlorate of potash also contains
cane sugar, which is in granulated form.
The core 3 is built about a glass tube 4 closed
45 at both ends, the tube containing sulfuric
acid. One end of the tube is supported on a
lug 5 within the shell opposite the opening
into which the closing plug 6 fits. This plug
has also a seat 7 for the other end of the tube.

50 A shock to the shell ruptures the glass
container 4 and allows the sulfuric acid to
react with the chlorate. The chlorin re-
sulting from the reaction interacts with the
hydrogen of the hydrocarbons present, and

the double action of the acid on the chlorate
and the chlorin on the hydrogen, results 55
in spontaneous combustion, which, in turn,
causes the explosion of the propelling explosive
2. The presence of the cane sugar in
the mixture is not essential. It causes an in-
stantaneous deflagration thereby intensify- 60
ing the efficiency of the combustion set up
by the interaction of the sulfuric acid with
the chlorate moistened with turpentine and
mixed with the sugar.

I claim:

1. A shell of the character described com-
prising a fragile container containing acid,
a core about the container formed of a mix-
ture of potassium chlorate moistened with
hydrocarbons, a propelling explosive sur- 70
rounding said core, and a shell forming a
carrier for said explosive, core, and con-
tainer.

2. A shell of the character described com-
prising a fragile container filled with acid, 75
a core about the container formed of a mix-
ture of potassium chlorate moistened with
oil of turpentine, a propelling explosive sur-
rounding said core, and a shell forming a
carrier for said explosive, core, and con- 80
tainer.

3. A shell of the character described com-
prising a glass tube filled with sulfuric acid,
a core about the tube formed of a mixture
of potassium chlorate moistened with oil of 85
turpentine, a propelling explosive surround-
ing the core, and a shell housing the explo-
sive, core, and container.

4. A shell of the character described com-
prising a glass tube filled with sulfuric acid, 90
a core about the tube formed of a mixture
of potassium chlorate, granulated cane sugar
and oil of turpentine, a propelling explosive
surrounding said core, and a shell housing
said explosive, core and tube, said shell hav- 95
ing bearings for the end of said tube so that
a shock imparted to said shell will easily
break the tube.

5. In an explosive shell, a mixture adapted
to set off the explosive, the mixture consist- 100
ing of potassium chlorate, cane sugar and
oil of turpentine, and sulfuric acid separated
from the mixture by an easily fracturable
partition.

MOVSESS B. ADOM.
